UNITED STATES PATENT OFFICE.

HERMANN H. RIPPE, OF CLEVELAND, OHIO.

CAR-REPLACER.

SPECIFICATION forming part of Letters Patent No. 772,432, dated October 18, 1904.

Application filed February 29, 1904. Serial No. 195,802. (No model.)

To all whom it may concern:

Be it known that I, HERMANN H. RIPPE, a citizen of the United States, residing at Cleveland, in the county of Cuyahoga and State of Ohio, have invented new and useful Improvements in Car-Replacers, of which the following is a specification.

This invention is a car-replacer designed particularly for use in connection with the grooved rails of street-railways, and has for its object the provision of an improved device for replacing the car-wheels on the track. It is illustrated in the accompanying drawings, in which—

Figure 1 is a plan view. Fig. 2 is a longitudinal section. Fig. 3 is an end view showing the rail in section.

Referring specifically to the drawings, the replacer comprises an elongated inclined bar or block A, the incline proceeding at a slight angle from one end to the other, where it terminates in a curve extending sharply down to the base. The side edges of this block have upwardly-extending flanges B, producing therebetween a groove which receives the flange of the car-wheel when the device is in use. Projecting from the rear or butt end of the block, on the under side thereof, is a pivot-stud C, upon which is a block D, which is of proper size to fit in the groove of the rail E, as shown in Fig. 3. The inclined bar A may be turned upon the block D, by reason of its pivotal connection C, to place the bar at various angles with respect to the track. In

use the replacer is placed with the block D in 35 the groove of the rail, as shown in Fig. 3. The grooved bar is then turned to bring its point in line with the car-wheels, so that they will run up into the groove and being guided by the flanges roll off the butt of the replacer 40 onto the rail. The pivotal point being at the end, the construction is such that the groove at the butt of the replacer is always above the groove in the rail.

The device will be found very useful for the 45 purpose stated in connection with the replacing of cars upon grooved rails. The replacer requires no spiking or other fastenings, which, as may be imagined, is impracticable or difficult in paved streets.

What I claim as new, and desire to secure by Letters Patent, is—

1. A car-replacer comprising a grooved inclined bar pivoted at its butt, on the under side, to a block constructed to fit in the groove 55 of a rail.

2. A car-replacer comprising a block adapted to fit in the groove of a rail, and an inclined grooved bar having on the under side of the butt thereof a pivot-stud connecting it 60 to the block.

In testimony whereof I have signed my name to this specification in the presence of two subscribing witnesses.

HERMANN H. RIPPE.
